UNITED STATES PATENT OFFICE.

DAVID O. WILKINS, OF OKLAHOMA, OKLAHOMA.

BRACE.

No. 885,819.

Specification of Letters Patent. Patented April 28, 1908.

Application filed April 30, 1907. Serial No. 371,083.

To all whom it may concern:

Be it known that I, DAVID O. WILKINS, a citizen of the United States, residing at Oklahoma City, in the county of Oklahoma, Oklahoma, have invented certain new and useful Improvements in Braces, of which the following is a specification, reference being had to the accompanying drawings.

My invention relates to improvements in a brace in which the handle is adapted to be detached and replaced by others of greater or less radial swing and the object of my invention is to provide an attaching means between the cranked handle and the head and socket ends of the brace that will join the several parts in a more efficient and rigid manner. This object I attain by means of the device illustrated in the accompanying drawing, in which

20 Figure 1 is a side elevation of the brace, part being shown in section; Fig. 2 is a cross-section on the line II—II, Fig. 1; Fig. 3 is a bottom view of the head attaching means having the sleeve clamp shown in section; 25 Fig. 4 is a perspective view of one end of the cranked handles, showing the crescent-shaped key attached thereto; Fig. 5 is a view in perspective of the swiveled socket clutch or nipple adapted to the head end of the 30 brace, and Fig. 6 is a perspective view of the tapered sleeve adapted to fit over the tapered portion of the swiveled socket clutch.

In the drawings, in which each numeral refers to the same part in the several figures, 35 1 is the ordinary socket or bit-clamping member at the upper end of which projects at right angles thereto the taper nipple or slotted socket 2, provided in its upper wall with a slot of a width equal to the bore of the 40 nipple. This nipple is of exactly similar form to that forming a part of the nipple member which carries the pressure-receiving head 5 at the upper end of the spindle 6. The upper nipple member is shown in perspective in Fig. 5, and comprises a barrel portion 7 having a central bore 8 and the nipple 9 at right angles to the barrel 7. Nipple 9 is also provided with a central bore and its wall slotted through to form the U-shaped groove 45 10. Within the bore 8 is mounted the spindle 6 which is rotatably secured to nipple 9 by means of collar 11, washer 12 and screw 13. Midway of the length of nipples 2 and 9 are pin holes 14 and 15, and corresponding

thereto in the arms or tongues 15 and 16 of 55 the cranked handle 17 are threaded holes 18 and 19.

Referring to Fig. 4, 20 designates a wedge-shaped protuberance or key which is shaped on one face to conform to arm or tongue 15 of 60 the cranked handle with which it may be made solid by brazing. This key is provided with a hole to correspond with the threaded hole 18 and where this cuts the convex surface key is counter sunk to receive the 65 counter sunk head of a screw 21. Screw 21 is provided on its other end with a smooth pin portion 22 of the proper size to fit into the hole 14 of nipple 9. It will thus be seen that the threaded pin 21 may act in a two-fold 70 capacity, first, to secure the wedge-shaped key 20 to the arm 15 should it not be brazed thereon, and secondly, to furnish a pin 22 to restrain said arm and key from slipping lengthwise from the nipple. As a serviceable 75 and efficient means for retaining the various parts of this coupling means in place, an outer taper sleeve 23 is used. As shown in Figs. 1 and 3, the inner surface of sleeve 23 is tapered to correspond to the taper on the outer surface of nipple 9 so that when sleeve 23 is driven into place upon the nipple 9, the arms of the cranked handle are compactly and rigidly secured to the said nipples. The 80 coupling members made use of to attach arm 16 to the bit-clamping member are of exactly the same construction as those already disclosed in connection with the arm attaching member of the pressure-receiving head.

Having thus described my invention, what 90 I claim as new, and desire to secure by Letters Patent, is:—

1. In a brace, a coupling for attaching the pressure receiving head to the double armed crank, said coupling comprising a hollow 95 nipple carried by the pressure receiving head and provided with slotted taper walls, a coupling member, carried by the double armed crank and provided with a wedge shaped key attached thereto in such manner 100 as to adapt it to fit into and fill the hollow space in said tapered nipple, and a sleeve tapered interiorly to correspond to said tapered nipple by which means it is adapted to slide on to and clamp the tapered sleeve upon the 105 crank arm.

2. In a brace, the combination with a pressure receiving head and a crank handle, of a

coupling for connecting them together said coupling comprising a slotted hollow taper nipple having a pin hole therein and journaled upon the pressure receiving head, a 5 wedge-shaped protuberance secured to the arm of said crank handle whereby said crank handle end is adapted to fit into and fill the hollow in said nipple, a pin projecting from the end of the crank arm and adapted to engage with the pin hole in said nipple, and a taper sleeve movable longitudinally along the axis of the crank arm and nipple whereby the coupling may be made rigid.

3. In a brace, the combination with the 15 pressure receiving head, a bit-chucking member, and a double armed crank handle, of hollow slotted nipples swiveled upon the head and bit-chucking members respectively and adapted to receive the arms of the crank handle, each of said nipples being provided with a pin hole, a pin projecting from each arm of the crank handle and adapted to engage in said pin hole to prevent relative longitudinal movement between nipple and arm and a 25 key rigidly secured to each arm of the crank handle whereby is prevented a relative rotary movement between said nipples and arms.

4. In a brace, the combination with a pressure receiving head, a bit-chucking member, 30 a double armed crank handle, tapered coupling members carried by the pressure receiving head and bit-chucking members respectively, each of said coupling members being provided with a central bore and having a 35 slot throughout the length of the taper on said coupling whereby it is adapted to receive the arms of the crank handle; keys secured to the arms of the crank handles and proportioned to fit into the slots in said clutch members whereby they are prevented turning 40

therein, and a taper sleeve adapted to fit said coupling to make a rigid joint.

5. In a brace, the combination of a pressure receiving head, a bit chuck, a double armed crank handle and means for detachably connecting each of the arms of the crank handle to the pressure receiving head and the bit chuck, the said means comprising a hollow slotted coupling member provided with a pin hole secured to one of said members at right angles thereto, a wedge shaped key secured to the other of said members and fitting the slot of the clutch member, a pin projecting from an arm of the crank handle and adapted to engage the pin hole in the 50 slotted coupling member, and a sleeve sliding upon said slotted coupling member to retain the several parts in position.

6. In a brace having a pressure-receiving head, a bit-chucking member and a detachable crank handle with two arms, a clutching means for connecting one of said arms to the pressure-receiving head and the bit-chucking member respectively, the said clutching means comprising a slotted taper nipple having a pin hole therein opposite to the slot, a crescent shaped key seated upon each arm of the crank handle, a threaded pin for securing each key to said arm, said pin extending therethrough and into the pin hole in the 60 slotted nipple; and a taper sleeve adapted to be driven upon the tapered nipple in such manner as to clamp the arm of the crank handle therein.

The foregoing specification signed at Oklahoma City, Okla., this 4th day of March, 1907.

DAVID O. WILKINS.

In presence of—

CHAS. EDWARD JOHNSON,
I. L. PRICE.
